US00D734752S

(12) **United States Design Patent**
Chen et al.

(10) **Patent No.:** US D734,752 S
(45) **Date of Patent:** ** Jul. 21, 2015

(54) **WIRELESS SCANNER**

(71) **Applicant:** **Foxlink Image Technology Co., Ltd.**,
New Taipei (TW)

(72) **Inventors:** **Chi-Wen Chen**, New Taipei (TW);
Chun-Yuan Sun, New Taipei (TW);
Chia-Hsiang Wang, New Taipei (TW);
Yen-Chi Wu, New Taipei (TW)

(73) **Assignee:** **FOXLINK IMAGE TECHNOLOGY
CO., LTD.**, New Taipei (TW)

(**) **Term:** **14 Years**

(21) **Appl. No.:** **29/509,472**

(22) **Filed:** **Nov. 18, 2014**

(51) **LOC (10) Cl.** **14-02**

(52) **U.S. Cl.** **D14/420**

(57) **CLAIM**

The ornamental design for a wireless scanner, as shown and described.

DESCRIPTION

FIG. 1 is a perspective view of a wireless scanner showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another perspective view of the wireless scanner showing our new design.
